(57) **CLAIM**

The ornamental design for a handle arrangement for a reciprocating saw, as shown and described.

DESCRIPTION

FIG. 1 is a perspective view of a handle arrangement for a reciprocating saw showing our new design;

FIG. 2 is a left side view of FIG. 1;

FIG. 3 is a top view of FIG. 1;

FIG. 4 is a right side view of FIG. 1;

FIG. 5 is a bottom view of FIG. 1;

FIG. 6 is a front view of FIG. 1;

FIG. 7 is a rear view of FIG. 1;

FIG. 8 is a perspective view showing our new design in an alternative position for use;

FIG. 9 is a left side view of FIG. 8;

FIG. 10 is a top view of FIG. 8;

FIG. 11 is a right side view of FIG. 8;

FIG. 12 is a bottom view of FIG. 8;

FIG. 13 is a front view of FIG. 8; and,

FIG. 14 is a rear view of FIG. 8.

The present application is directed to the shape and contour of the design illustrated in the drawings. The power supply and portions of the reciprocating saw shown in broken lines are for illustrative purposes only and form no part of the claimed design. The broken lines shown within the boundaries of the claimed surfaces are superimposed on continuous, uninterrupted surfaces and are for illustrative purposes only and form no part of the claimed design.
